P. P. HINOTE

BATTERY TERMINAL CLAMP PULLER

Filed April 27, 1928

WITNESS: *J. L. Wright*

Paul P. Hinote
INVENTOR
BY *Victor J. Evans*
ATTORNEY

UNITED STATES PATENT OFFICE.

PAUL PHILLIP HINOTE, OF UNIONVILLE, IOWA.

BATTERY TERMINAL CLAMP PULLER.

Application filed April 27, 1928. Serial No. 273,336.

This invention relates to a battery terminal clamp puller, the general object of the invention being to provide a cross piece having a jaw pivoted to each end thereof, with a recess at the center of the cross piece for receiving a nut through which a threaded shaft passes, with a handle at one end of the shaft and its other end pointed to engage a terminal while the jaws are engaging the clamp on the terminal so that by screwing the shaft downwardly, the clamp will be forced from the terminal.

Another object of the invention is to form the cross piece of two members which are spaced apart by the jaws so that the shaft and its handle can be passed between them and the nut removed from the recess so that the device can be used as a handle for carrying a battery, with the lower edges of the two parts of the cross piece rounded to prevent injury to the hand gripping the cross piece.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation showing how the device is used to remove a clamp from a battery terminal.

Figure 2 is an edge view of the device.

Figure 3 is a section on line 3-3 of Figure 1.

Figure 4 is a top plan view of the device.

Figure 5 is a detail view showing the recess for the nut, this view also showing the nut.

Figure 6 is a view showing how the shaft and its handle may be passed between the two parts of the cross piece.

Figure 7 is a view showing how the device is used to carry a battery.

In these views, the cross piece is shown at A, and it is composed of the two members 1 having their lower edges rolled as at 2 and having their central portions offset outwardly to form the recesses 3. The upper ends of the jaw members 4 are placed between the members 1 and are pivotally connected there-

with by the pins 5. Thus the jaws space the two members 1 apart. A nut 6 has portions engaging the recesses 3 and said nut is provided with the oppositely arranged wings 7 formed with the downwardly and inwardly sloping upper faces 8 for receiving portions of the rounded parts 2 of the members 1, as shown in Figure 3. A screw shaft 9 passes through the nut and has a handle 11 at its upper end. The lower end of the shaft is pointed to engage a terminal of the battery, as shown in Figure 1. A chain 12 connects the nut with a part of the cross piece.

From the foregoing it will be seen that when the nut is placed in the recesses 3 and the hooked ends of the jaws 4 placed under the clamp C of a battery B, with the end of the shaft engaging the top of the terminal T of the battery, by turning the shaft, pressure will be exerted by the jaws on the under side of the clamp C and thus the clamp will be forced from the terminal.

When the device is to be used as a handle for carrying a battery, as shown in Figure 7, the shaft and its handle are pressed downwardly to free the nut from the cross piece and the handle passed between the two members 1 of the cross piece so that the shaft and nut will hang free by the chain and thus the entire cross piece can be used as a hand grip, the rounded portions preventing injury to the hand of the user.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:

1. A device of the class described comprising a cross piece composed of two members each having an internal recess at its center, with the lower edge of each member rolled, a pair of jaws having their upper ends pivoted between the members of the cross piece at the ends thereof, a nut removably seated in the recesses and having wings forming seats for the rounded portions of the members of the cross piece, a screw shaft passing through the nut, a handle on the upper end of the shaft and a chain connecting the nut with a part of the cross piece.

2. A device of the class described comprising a cross piece composed of two members each having an internal recess at its center, with the lower edge of each member enlarged, 5 a pair of jaws having their upper ends pivoted between the members of the cross piece at the ends thereof, a nut removably seated in

the recesses and having wings forming seats for the enlarged portions of the members of the cross piece, a screw shaft passing through 10 the nut and a handle on the upper end of the shaft.

In testimony whereof I affix my signature.
PAUL PHILLIP HINOTE.
